CAN OPENER

Robert H. Waller, Nashville, Tenn.

Application August 5, 1948, Serial No. 42,690

7 Claims. (Cl. 30—15)

1

This invention relates to can openers and an object of the invention is to provide a device of this kind including a drive or traction member and a coacting cutting member carried by a swinging lever which lever also serves as a means for controlling a stop member.

It is also an object of the invention to provide a device of this kind including a body member with which is operatively engaged a swinging lever carrying a cutting means and wherein a stop member is slidably mounted on the body member and operatively engaged with the lever in a manner whereby the lever when moved to bring the cutting means into effective engagement with a can also moves the stop member to effective engagement with the can and vice versa.

A further object of the invention is to provide a device of this kind comprising a body member on which a traction or drive wheel is mounted together with a stop member movable on the body toward and from the drive or traction wheel and wherein a lever for moving a cutting means into and out of effective position also serves to move the stop member toward or from the drive or traction wheel.

The invention consists in the details of construction and in the combination of the several parts of my improved can opener whereby certain advantages are attained, as will be herein-after more fully set forth.

In order that my invention may be better understood, I will now proceed to describe the same with reference to the accompanying drawings, wherein:

Figure 1 is a view in front elevation of a can opening device constructed in accordance with an embodiment of the invention;

Figure 2 is a view in side elevation;

Figure 3 is a sectional view taken substantially on the line 3—3 of Figure 1;

Figure 4 is a sectional view taken substantially on the line 4—4 of Figure 1;

Figure 5 is a fragmentary view in elevation of another embodiment of the invention; and

Figure 6 is an enlarged detail sectional view taken substantially on the line 6—6 of Figure 5.

As disclosed in the accompanying drawings, M denotes a body member illustrated as an elongated flat plate of desired dimensions and configuration. The lower portion of the member M is herein disclosed as reduced in width, as at 1, and provided with an outstanding lip or flange 2 with which is rotatably engaged from below a wheel 3. This wheel 3 is adapted to engage and ride on the periphery of a can during a working operation.

2

Above but closely adjacent to the lip or flange 2 the outer face of the member M has rotatably mounted thereon a drive or traction wheel 4, the periphery of which is toothed or knurled to assure effective engagement with the can to be opened. This wheel 4 is mounted on a shaft 5 disposed through the member M and has engaged therewith a thumb and finger crank 6 at the side of the member M opposite to the wheel 4.

The body member M above the wheel 4 is provided with a slot 7 disposed lengthwise of the member M and substantially radial of the axial center of the wheel 4. Outwardly beyond the slot 7, the member M is provided with a second slot 8 substantially at right angles to the slot 7 and which extends to one side of the slot 7 whereby the slots 7 and 8 combine to provide what may be generally or broadly termed as an inverted L slot.

Slidably mounted on the member M below the slot 8 is a plate 9 having its inner marginal portion provided with an outstanding stop element 10 which preferably possesses a certain degree of inherent resiliency or flexibility so that in practice the device as a unit may be effectively employed with cans of varying sizes within certain limitations.

Extending in a general direction lengthwise of the body M is an elongated lever 11 which also overlies the sliding plate 9. The inner extremity of the lever 11 is formed to provide a cutting blade 12 which is adapted to penetrate an end wall of the can when the device is in operation.

The lever 11 inwardly of the blade 12 has disposed therethrough a part 14, such as a screw, which is also directed through the plate 9 and the slot 7 of the member M, whereby the lever 11 and plate 9 are pivotally engaged. The lever 11 at the required distance outwardly from the part 14, carries a second part 15, also shown as a screw, which rides in the slot 8.

As shown in the accompanying drawings the outer portion of the lever 11 is formed to provide a cap or top remover 16 while the outer portion of the member M is formed to provide a screw driver blade 17 which also forms a handle or holding means.

In practice, the device is applied against a can with the wheel 4 below the chine a of the can and the stop element 10 lying over or across the edge of the can and of course with the lever 11 in a position to raise the cutting blade 12.

The lever 11 is then properly swung to cause the blade 12 to penetrate the adjacent end wall of the can and at the same time effect the downward movement of the plate 9 to bring the same

into effective engagement with the can edge and to maintain desired contact of the wheel 4 with the chine a to assure desired travel of the device around the can as the wheel 4 is rotated or should the device be held stationary, to effect desired rotation of the can.

When the lever 11 is at the limit of its movement to effect penetration of the cutting blade 12, it is past its center of swinging movement to assure the maintenance of the cutting blade in desired position throughout the cutting operation.

In the embodiment of the invention as illustrated in Figures 5 and 6, the general construction and assembly is the same as comprised in the first embodiment, except that the stop means carried by the sliding plate 18 on the body member B comprises two transversely spaced rollers 19 rotatably carried by the lower corner portions of the plate 18.

From the foregoing description it is thought to be obvious that a can opener constructed in accordance with my invention is particularly well adapted for use by reason of the convenience and facility with which it may be assembled and operated.

I claim:

1. A can opener including a body plate, a traction wheel mounted thereon, a swinging lever operatively mounted on the body plate and having a cutting means, said traction wheel engaging the chine of a can upon rotation of the wheel, means for rotating the wheel, a plate member slidably mounted on the body plate for movement toward and from the traction wheel, and an operative connection between the plate member and the lever whereby the plate member is moved toward the traction wheel when the lever is moved in a direction to make effective the cutting means and vice versa, the body plate being provided with perpendicularly related slots, and parts carried by the lever working in said slots.

2. A can opener including a body member, a traction wheel mounted on the body member, a swinging lever operatively mounted on the body member and having a cutting means, the traction wheel being adapted to engage the chine of the can upon rotation of the wheel, means for rotating the wheel, a plate slidably mounted on the body member for movement toward or from the traction wheel, an operative connection between the plate and lever whereby the plate is moved toward the traction wheel when the lever is moved in a direction to make effective the cutting means and vice versa and a stop element carried by the plate for engagement against the top of the can.

3. A can opener, comprising a long flat body plate, having means at one end providing a handle, a rotary drive wheel pivotally supported on the plate at one side face thereof, means for turning said wheel, a plate disposed across the said one side face of the body plate between the handle and wheel and coupled with the body plate for sliding movement thereon, means carried by

the second mentioned plate for engagement with the top edge of a can, a lever pivoted adjacent to one end on the second plate to swing on an axis parallel to the rotary axis of the drive wheel, a cutter upon the said one end of the lever extending beyond the said can edge engaging means, and a pivotal and sliding fulcrum coupling between the lever and the body plate and movable across the length of the body plate, by which the said cutter is shifted relatively to the wheel and the second plate is caused to slide on the body plate when the lever is swung on its pivot.

5. A can opener of the character described in claim 3, wherein the said means carried by the second mentioned plate for engagement with the top edge of a can comprises an integral right angle extension of a portion of the second mentioned plate, said extension having an opening therein through which said cutter projects.

10 6. A can opener of the character stated in claim 3, wherein the said means carried by the second mentioned plate for engagement with the top edge of a can comprises two roller members supported upon the second mentioned plate and spaced apart transversely of the body plate, the said cutter upon the said one end of the lever being disposed between the rollers.

15 7. A can opener of the character stated in claim 3, wherein the said pivotal and sliding fulcrum coupling between the lever and the body plate comprises a slot formed in the body plate in a direction transversely thereof and located between the second mentioned plate and handle and an element carried by the lever and slidably engaged in said slot.

20 8. A can opener of the character stated in claim 3, wherein the body plate has a portion of the end thereof upon the side of the drive wheel remote from the second mentioned plate turned to extend laterally from the said one side face, and a roller element pivotally supported upon the laterally turned end portion of the body plate to rotate on an axis extending lengthwise of the body plate, said roller being adapted to engage the side wall of a can when the opener is in operative position thereon.
